CALVIN B. PATCH, OF GLENELLYN, ILLINOIS, ASSIGNOR TO WILLIAM H. MINER, OF CHAZY, NEW YORK.

DETACHABLE CONNECTION FOR STANDARD DRAW-BARS AND YOKES.

1,286,756.

Specification of Letters Patent.

Patented Dec. 3, 1918.

Application filed February 5, 1917. Serial No. 146,577.

To all whom it may concern:

Be it known that I, CALVIN B. PATCH, a citizen of the United States, residing at Glenellyn, in the county of DuPage and State of Illinois, have invented a certain new and useful Improvement in Detachable Connections for Standard Draw-Bars and Yokes, of which the following is a full, clear, concise, and exact description, reference being had to the accompanying drawings, forming a part of this specification.

This invention relates to improvements in detachable connections for standard draw bars and yokes.

The object of the invention is to provide a detachable connection for draw bars and yokes of standard construction wherein are utilized the usual rivet holes provided in the draw bar butt and yoke straps, the parts being so arranged that the detachable connections between the parts are placed under double shear.

In the drawing forming part of this specification, Figure 1 is a side elevation of portions of a draw bar and yoke strap, showing my improvements in connection therewith. Fig. 2 is a central, vertical longitudinal section of the structure illustrated in Fig. 1. Figs. 3 and 4 are transverse, vertical sectional views, taken substantially on the lines 3—3 and 4—4 respectively of Fig. 1. And Fig. 5 is a detail perspective of one of the lug plates employed with my construction.

In said drawing, 10 denotes a draw bar having a butt 11 provided with the usual upper and lower shoulders 12 and 13 and the usual standardly spaced rivet holes 14—14 in the upper and lower walls thereon. The draw bar is also provided with the usual coupler-key slots 15—15 in the opposite side walls thereof. The yoke which is employed with the draw bar is or may be of the usual strap form having upper and lower arms 16—16, the latter being also perforated, as indicated at 17, which perforations are in alinement with the holes 14 of the draw bar butt, when the draw bar and yoke are properly assembled.

The detachable connection proper, as shown, comprises an upper lug plate 18, lower lug plate 19, and detachable side plates 20—20. The lug plate 18 is formed with a pair of integral lugs 21—21, which are adapted to extend through the perforations 17 and 14 in the upper yoke arm and upper

wall of the draw bar butt. The lower lug plate 19 is similarly provided with a pair of integral lugs 22—22 to penetrate the lower holes of the draw bar butt and lower yoke arm. The plate 18 is recessed on its upper face, as indicated at 23, thus forming side ribs 24—24 and front and rear ribs 25—25. Each of the side plates 20 is hook-shaped at its upper end, as indicated at 26, to thereby fit over the side ribs 24, it being apparent that longitudinal movement of said plates 20 relatively to the lug plate 18 is prevented by the front and rear ribs 25 on the latter. The lower lug plate 19 is provided at each side thereof with an extension 27 of lesser width than the main body of the plate 19, said extensions 27 being received in corresponding slots 28—28 in the lower portions of the side plates 20. To facilitate applying the plates 20 over said extensions 27, the under faces of the latter are beveled, as indicated at 29. After the plates 20 are properly assembled with the lug plate 19, they may be held in position by cotters 30.

From the preceding description, it will be seen that the four plates 18, 19, and 20—20 form, when assembled, a band which surrounds the draw bar butt and the yoke arms, and, in conjunction with the lugs 21 and 22, serve to detachably connect the draw bar and yoke.

It is desirable that the lugs 21 and 22 be placed under double shear to thus provide double the resistance in preventing separation of the draw bar and yoke. To accomplish this, each of the side plates 20 is provided with a forward extension 31, each extension 31 having on its inner face an integral short semi-key or lug 32 of suitable formation to be swung into and out of the corresponding coupler key slot 15 when the plates 20 are in engagement with the plate 18. In this manner it is apparent that the draw bar will pull on the side plates 20 through the semi-keys 32, and the side plates 20 in turn will pull upon the lug plates 18 and 19, thus placing the lugs 21 under double shear.

The parts are shown in the drawing in assembled position, and in order to disconnect the draw bar and yoke, the cotters 28 are first removed, after which the lower ends of the plate 30 are swung outwardly sufficiently to clear the lug plate 19, whereupon the latter may be dropped down. Then

the side plates 20 can be disconnected by merely lifting the same sufficiently to disengage the upper lug plate 18. The side plates 20 having been removed, the lug plate 18 can be taken off by lifting the same vertically. The parts are assembled by reversing the sequence of the operations just described.

I claim:

- 10 1. In a detachable connection for draw bars and yokes having alined holes when assembled, the combination with upper and lower members each having inwardly extending lugs adapted to penetrate said holes, of side plates extending between said upper and lower members, said side plates and upper and lower plates having integrally formed coöperating means for detachably uniting said plates and members.
- 15 2. In a detachable connection for draw bars and yokes having alined holes when assembled, a four-sided band arranged to surround the draw bar butt and yoke, the upper and lower members of said band having means adapted to penetrate said holes and the side members having inwardly extending lugs located so as to engage in slots of the draw bar.
- 20 3. In a device of the character described, the combination with a coupler having a coupler-key slot and the usual rivet holes

in the butt thereof, of a yoke having the arms thereof provided with holes in alinement with the holes of the coupler butt, upper and lower plates fitting over the upper and lower arms of the yoke and having lugs penetrating the holes of the yoke arms and the holes of the draw bar butt, and side plates detachably connected to both of said lug plates, said side plates having also lugs arranged to enter the coupler-key slot.

4. In a device of the character described, the combination with a draw bar having the butt thereof provided with standardly spaced rivet holes, of a yoke having the arms thereof provided with holes alined with those of the draw bar butt, an upper lug plate having lugs penetrating the upper holes of the yoke and draw bar butt, a lower plate having lugs penetrating the lower holes of the draw bar butt and yoke, and side plates for detachably connecting the lug plates, each of said side plates having a detachable hook connection with the upper lug plate and slotted at its lower end to receive a portion of the lower lug plate.

In witness that I claim the foregoing I have hereunto subscribed my name this 31st day of Jan., 1917.

CALVIN B. PATCH.
